UNITED STATES PATENT OFFICE.

JAMES MALLOL, OF BIRMINGHAM, ENGLAND.

INCANDESCENT GAS-BURNER.

SPECIFICATION forming part of Letters Patent No. 685,623, dated October 29, 1901.

Application filed August 31, 1901. Serial No. 78,989. (No model.)

To all whom it may concern:

Be it known that I, JAMES MALLOL, electroplate-manufacturer, a subject of His Majesty the King of Spain, residing at 176 Warstone Lane, in the city of Birmingham, England, have invented certain new and useful Improvements in Incandescent Gas-Burners, of which the following is a specification.

This invention has reference to incandescent gas-burners; and it consists of the herein-described improvements whereby I obtain a better light than heretofore from the same amount of gas, and the burner is simplified and will last longer in wear and is not liable to become choked.

An incandescent burner of the class heretofore used is open to the objection that not only is the speed of the mixture of gas and air diminished, but the flame is prevented from taking sufficient air from the outside as to raise the temperature of the flame high enough to give the best results, and, moreover, as the gauze gets clogged with particles of carbon the heat of the flame is very much reduced. In a burner having the slits cut radially in direct lines toward the center, the spaces between the slits, although small, are sufficiently large to supply too much air to the flame, so that the supply of air to the gas issuing through the nozzle has to be checked by interposing a wire-gauze or by other means, the result being a flame of much lower temperature than it is possible to obtain when the burner is constructed according to my invention. On the other hand, if the gas takes too much air from the inside of the burner the flame burns with an objectionable roar, owing to the large amount of air that passes between the slits. In addition to the above defects these classes of burners are open to the very serious objection of forming a very thick annular flame if sufficient gas is to be consumed to fill the cavity of the mantle, so that a lot of gas is burning to waste, as only that part of the flame which comes in contact with the mantle produces the result of raising it to high incandescence. Considering that a flame has a higher temperature the greater the quantity of air mixed with the gas till it reaches its chemical equivalent and that speed in the flame is most important to supply the heat radiated by the mantle, the burners described

appear to be constructed on wrong principles, and I construct mine in the following manner, and thereby obtain better results than heretofore.

I will describe my invention by referring to the accompanying drawings, on which—

Figure 1 is a sectional elevation of an incandescent gas-burner constructed in accordance with this invention. Fig. 2 is a plan of the same with the crutch and mantle removed. Fig. 3 shows separately some of the parts of which the burner is formed. Fig. 4 is a sectional elevation, and Fig. 5 is a sectional elevation and plan, of two other parts of the said burner. Fig. 6 is a sectional elevation, on an enlarged scale, of a part of the same. Fig. 7 is a sectional elevation, and Fig. 8 is a side elevation and plan, of a modified form of the toothed cone part of the said burner.

The same reference-numerals indicate the same parts in all the figures.

Screwed to the upright tube 1 of the burner is a socket 2, of inverted conical or cup shape, having a threaded recess 3 at the top, into which screws a cylindrical tube 4, thus forming what is known as the "mixing-chamber." Fitting in the top of the cylindrical tube or mixing-chamber 4 is a solid inverted cone 5, the lower portion 6 of which is an inverted truncated cone of about one-half the length of the complete cone, the upper portion 7 being by preference hollowed at the top, having a central boss 8, which is bored to receive the ordinary crutch 9 to support the mantle 10. The upper portion of the cone 5 has teeth 11 cut in it by a wheel-cutting machine or by other suitable means, these teeth extending from the top for a certain distance down, the apertures between the teeth 11 forming the outlets through which the mixed air and gas issues as it is burned. The tips of the teeth 11 just touch or very nearly touch the interior of the tube 4. The teeth 11 may be straight or oblique, and they form knife-edged ribs down to about the middle of the cone, which become heated when the burner is lighted and heat the gaseous mixture as it rises up between them. To give the best results, the number and depth of the teeth are important. I find that if the cone is about one inch in diameter then about forty-four teeth, as shown, give the best results; but if the num-

ber of teeth are in this diameter diminished to below thirty the flame is liable to fire back. A suitable depth for the teeth is about one-eighth of an inch.

5 The toothed cone 5 above described is by preference made of metal; but it may be made of steatite or other suitable substances.

To prevent the possibility of the flame firing back and also to insure the proper mixing 10 of the air and gas as well as the heating of the gaseous mixture, I provide around the toothed cone 5 a truncated cone 12, of wire-gauze or perforated metal, which is a little larger at its narrowest part 13 than the cone 15 5 and is rather shorter, the toothed cone 5 projecting through it, (see Fig. 1,) the diameter of the upper part 14 being about the same as that of the solid cone 5. This wire-gauze or perforated cone 12 is by preference 20 made of copper, and when made of gauze is rolled, so that the wires are flattened and pressed together, having the appearance of perforated metal.

The two cones 5 and 12 are suitably supported 25 inside the mixing-chamber 124 by the star-shaped piece 15, made with, say, three radial arms 16, which project outwardly at the lower part of the cone 5 and fit exactly into and between the screw-threads in the recess 3 of the socket 2, the arms 6 being formed with a central boss 15^a, through which passes the screw 17, which is screwed into the cone 5 to secure the star-shaped piece 15 thereto. This screw 17 is made with an inverted somewhat-conical head 18, so as not to obstruct 35 the gaseous mixture passing up through the mixing-chamber. The upper part 19 of the screw 17 fills up the lower part of the hole 8 in the cone 5, as otherwise the hole 8, in which 40 the crutch fits, would be too deep.

The Bunsen-burner part is made differently to those at present in use, the object being to provide a complete burner short enough to screw onto any gas-fitting like an ordinary 45 gas-burner without the mantle projecting above the ordinary glass globe, so that the burner can be used with any globe and fittings without the expense of special ones, as at present. In making the Bunsen-burner 50 part I provide a taper screwed nipple 20 for screwing into any ordinary gas-fitting and made with a disk 21, having a projecting milled rim 22, the nipple also projecting at 23 above the disk 21, and the nipple has a 55 central hole 24, which widens toward the top and forms a sort of tube, in the top of which is spun a thin circle of metal 25, (shown separately on enlarged scale in Fig. 6,) having three small holes 26, which are at sufficient 60 distance from each other to form three gas-jets slightly inclined outwardly, so as to properly mix with the incoming air. The disk part 21 of the nipple is perforated with vertical holes 27, up which the air passes. 65 Screwed onto the disk part 21 is a slightly-tapered tube 28, having an inverted-funnel shape 29 at the bottom and screwed inter-

nally at 30, thus, with the nipple 20, forming the Bunsen burner, the air entering from underneath through the holes 27 in the disk 21, 70 as indicated by the arrows in Fig. 1, instead of entering sidewise, as usual. The top 31 of the tube 28 is countersunk to a fine edge inside, so as to prevent the formation of a shoulder inside. The mixture of air and gas 75 will burn in the burner without firing back notwithstanding its short length, and when the tube, with the part 1 of the previously-described top part of the burner, is fitted outside the tube 28 and the crutch 9 and mantle 80 10 are in position the incandescent burner is complete.

When my invention is used for public lighting or in other public places where a hissing noise in the burner is no objection, the Bunsen burner may be made with only one of the jet-holes 26 in the center of the disk 25 instead of the three jets above described, the top part in this case being made some few 85 inches higher to prevent flashing back. 90

In the modification of my invention illustrated in Figs. 7 and 8 instead of employing the solid cone 5, as above described, with the teeth 11 cut or formed in it, I make the cone 5 by stamping from sheet metal with a fluted 95 edge 32 and finish it with tolls in a press, and as it is not possible in this case to make the grooves between the flutes 32 deep enough to give sufficient area for the gaseous mixture to pass through if the tips of the flutes touch 100 the interior of the tube 4 a small annular space 33 is left between the cone 5 and the interior of the cylindrical tube part 4 of the mixing-chamber, as shown in the plan view, Fig. 8. 105

The cone 5 is by preference hollowed at the top, so that the top part and ribs 11 will be heated to a high temperature by the flame and will thus heat to a high temperature the gaseous mixture which rises up between the 110 teeth, and thereby increase the efficiency of the burner.

What I claim as my invention, and desire to secure by Letters Patent, is—

1. In an incandescent burner, the combination with the burner-tube having a mixing-chamber in the upper part thereof, of an inverted cone located in said chamber and having a plurality of ribs on its surface and a perforated cone surrounding said ribbed cone, 115 substantially as described.

2. The combination with the burner-tube having a mixing-chamber, of a star-shaped piece having its arms engaging the walls of said mixing-chamber, and an inverted ribbed 120 cone supported on said star-shaped piece, substantially as described.

In witness whereof I have hereunto set my hand in presence of two witnesses.

JAMES MALLOL.
